SWEATER

Hans Boepple, New York, N. Y.

Application August 30, 1956, Serial No. 42,779

Term of patent 7 years

(Cl. D3—4)

Fig. 1

Fig. 2

Fig. 1 is a plan view of one side of a sweater showing my new design; the other side being substantially the same as the side shown; and

Fig. 2 is an enlarged fragmentary view of the same, showing the embroidered trim detail.

The characteristic feature of my design resides in the embroidered ornamentation on the sweater body, consisting of alternate rows of solid and eyeletted figures arranged in staggered relationship, as shown.

I claim:

The ornamental design for a sweater, substantially as shown and described.
